UNITED STATES PATENT OFFICE.

WALDO FRIEDRICH HERRMANN STRELOW, OF HAMBURG, GERMANY.

PROCESS FOR MANUFACTURING SHELLS FOR BODIES OF SHIPS.

Application filed October 5, 1921. Serial No. 505,549.

To all whom it may concern:

Be it known that I, WALDO FRIEDRICH HERRMANN STRELOW, citizen of Germany, residing at Hamburg, Germany, have invented 5 certain new and useful Improvements in a Process for Manufacturing Shells for Bodies of Ships, of which the following is a specification.

The present invention refers to a process 10 for manufacturing the outer shells of the bodies of ships. The object of the invention is to simplify the manufacturing of such shells.

Fig. 1 shows the body of a ship built up 15 according to the present invention.

Fig. 2 is a diagrammatical view, illustrating the method of manufacture.

According to the present invention the shell is made of a single sheet, built up by 20 riveting or otherwise connecting relatively small metal plates *a*, to form a relatively large, continuous sheet. The thus formed sheet is then bent upwards, beginning at its longitudinal center line, to form a shell *b* 25 as shown in Fig. 2 in dotted lines. After having been bent to this shape, a stem *c*, a frame *d*, stringers *e* and bulkheads *f*, are attached within the shell, and finally a stern *g*, preferably of sheet metal, and brought to 30 the desired form in any usual manner, is fastened to the stern end of the body. Thus it will be seen that the bodies of ships are built up with great facility and in a comparatively short space of time.

35 I claim:

1. A method for forming a sheet metal

shell of a ship body, comprising, forming a sheet of sufficient size to form a complete shell by means of connecting together a plurality of relatively small metal plates, then bending the thus formed sheet about a longitudinal center line to form the complete shell, fitting a stem to the bent metal sheet, inserting ribs and stringers into the shell, fitting a bulkhead to the rear portion of the shell, and attaching a stern to the shell and the bulkhead. 45

2. A boat hull comprising, a fabricated metal sheet shaped to form the major portion of the hull, a stem fitted to the metal hull, ribs and stringers positioned inside the metal hull, a separate bulkhead closing the rear of the hull, and a shaped metal stern fitted to the rear of the hull, and connected to the bulkhead and the fabricated metal sheet. 50

3. A method for forming a sheet metal shell of a ship body comprising, forming a sheet of sufficient size to form a complete shell by means of connecting together a plurality of relatively small metal plates, then bending the thus formed sheet of a longitudinal center line to form the complete shell, fitting a bulkhead to the rear portion of the shell, and attaching a stern to the shell and the bulkhead. 55 60

WALDO FRIEDRICH HERRMANN STRELOW.

Witnesses:

EMIL HAGER,
PETER LAUER.
